UNITED STATES PATENT OFFICE.

GRANVILLE A. HEIMER, OF PEN ARGYL, PENNSYLVANIA.

SOUNDING TOY.

1,234,472.

Specification of Letters Patent.

Patented July 24, 1917.

Application filed October 26, 1916. Serial No. 127,862.

To all whom it may concern:

Be it known that I, GRANVILLE A. HEIMER, a citizen of the United States, residing at Pen Argyl, in the county of Northampton 5 and State of Pennsylvania, have invented certain new and useful Improvements in Sounding Toys; and I do declare the following to be a full, clear, and exact description of the invention, such as will enable others 10 skilled in the art to which it appertains to make and use the same.

This invention relates to the general class of toys, but more particularly to certain new and useful improvements in sounding 15 toys.

The primary object of the invention is to provide a toy, which, when rolled over the floor or other surface, will be operated to produce a series of musical sounds.

20 Another object of the invention is to provide a toy of this character in which the musical sounds are produced by a plectrum which is caused to engage a series of strings, the method of mounting the plectrum being 25 unique.

A further object of the invention is to provide a device of this character which will be simple, comparatively strong, and extremely inexpensive in construction, and one 30 which will be efficient and reliable in operation, and well adapted to the purpose for which it is designed.

With these and numerous other objects in view, the invention consists of certain 35 novel features of construction, and the combination and arrangement of parts as will be hereinafter fully described and claimed.

The accompanying drawings illustrate the preferred form of the invention 40 wherein:

Figure 1 is a top plan view of a device constructed in accordance with this invention;

Fig. 2 is a horizontal sectional view taken 45 on the plane indicated by the line 2—2 of Fig. 3;

Fig. 3 is an end elevation of the barrel, one of the wheel members being removed;

Fig. 4 is an enlarged detail sectional view 50 through the stationary shaft, illustrating the manner in which the plectrum is mounted on the same;

Fig. 5 is an enlarged detail sectional view taken on the plane of the line 5—5 of Fig. 3.

55 Fig. 6 is a similar view taken through one end of the stationary shaft, showing the

manner in which it is engaged by one of the inturned ends of the handle;

Fig. 7 is a section taken on the plane of the line 7—7 of Fig. 6; and,

Fig. 8 is a detail perspective view of one 60 end of the stationary shaft, showing the modified form of connection of the handle with the same.

In the drawings, similar parts are designated by like reference characters throughout the several views, and in describing the invention, I shall refer to these parts by their respective indices.

Broadly stated, the invention comprises a 70 rotating member carrying the strings, a relatively stationary member arranged adjacent the rotating member, and a plectrum mounted upon the stationary member and adapted to engage the strings of the rotating member upon rotation of the same.

The stationary member is composed of a horizontally arranged shaft 1, the opposite ends of which are formed into axle spindles 2. The shaft 1 is here shown and is preferably of square-shaped structure in cross section and slightly larger in diameter than the spindles 2. The ends of the shaft are provided with apertures to receive the flattened ends of a handle 3. This handle 3 is 80 formed from a single length of comparatively heavy wire which is doubled upon itself at its central portion and twisted near its ends. The portions of the wire beyond its twisted portion are struck outwardly in 85 opposite directions, and then laterally into parallel relation, and these parallel members are then bent inwardly and flattened as at 4 for the above-mentioned connection.

Revolutely mounted upon the axle spindles 95 2 of the shaft 1 are circular disks or wheel members 5 having openings 6 arranged centrally therein to afford this mounting, and also to permit the spindles to extend to the interior sides of the same. Arranged horizontally between the wheel members 5 and secured at its ends to the latter in any convenient manner is a cylindrical barrel 7. Although this barrel is preferably cylindrical, yet it is to be understood that it may 100 be of any convenient shape in cross section.

Mounted upon the interior of the barrel 7 and extending longitudinally of the same from end to end is a series of strings 8. Any convenient means may be used for securing the ends of these strings 8 to the barrel, although it is preferable that they be 110

fastened by ordinary tacks 9. To space the strings a slight distance from the barrel so as not to come in contact with the same while in vibration, small staples 9' are 5 driven into the barrel adjacent the ends of the strings, their intermediate portions acting in the capacity of bridge members, as will be readily understood. It is to be here noted that when the device is strung, the 10 strings 8 are stretched so as to produce the desired musical note when caused to vibrate. They may be toned to the same note, or they may be toned to different notes. The latter is preferable.

15 The means for causing the strings 8 to vibrate consists of a yieldably mounted plectrum 10. This plectrum 10 is in the form of an ordinary round or substantially semi-spherical headed upholsterer's tack 11, 20 which is extended through the intermediate portion of an elastic strip of material 12, preferably of rubber. This strip 12 is secured at its ends to one of the flat sides of the shaft 1 by means of suitable fastening 25 elements, and when so fastened, the strip has sufficient elasticity to return the tack to its normal laterally extending position with respect to the side of the shaft to which it is fastened after it has been engaged by one of the strings 8. Close beneath the head of the tack 11 is a strip 13 of some soft material, such as paper, felt, or the like to provide a damper for the plectrum in order to prevent any squeaking 30 sound which might be caused by the rubbing of the head of the tack directly upon the shaft.

In using a device constructed as above, the handle 3 is grasped and the toy is moved 40 over the floor or other suitable surface. Owing to the fact that the ends of the handle are flattened and the openings 3 in the end of the shaft 1 are shaped so as to snugly receive them, the shaft 1 will be retained in a substantially stationary position, or at least, non-rotatable. As the device is pulled or pushed, the wheel members 5 will roll over the floor, and consequently rotate with respect to the shaft. 45 The strings 8 will be thus caused to successively engage the tack 11, which is moved out of its normal laterally extending direction with respect to the shaft to pass around said strings, the head of said tack, in effect, 50 having a rolling motion with respect to the flat side of the shaft with which it is maintained in contact by the elastic strip. As it disengages the strings, they will be caused to vibrate, thus producing the desired musical sound. The strip 12 which carries the 55 tack 11 will be stretched and distorted out

of its normal substantially flat position as the latter is moved angularly of the shaft. It will thereby be put under sufficient tension to return the tack to its normal position. 65

In Fig. 8 of the drawings, the end of the shaft 1 is shown provided with a screw eye 14 through which is inserted the adjacent end of the handle 3, said end of the handle 70 being formed into an eye 15 to prevent disengagement from the same. This construction provides a simple and efficient means for firmly securing the ends of the handle to the ends of the shaft, and in some instances will be found more convenient than the form shown in Figs. 1 to 7. 75

As various changes in form, proportion, and in the minor details of construction may be resorted to without departing from the spirit of this invention, I do not wish to be limited to the construction herein shown and described, other than that claimed. 80

I claim:—

1. In a device of the class described, the combination with two relatively movable members, one of said members having a series of strings thereon, a strip of elastic material secured at its ends to the other member, and a plectrum fixed to the intermediate portion of said strip, said plectrum being disposed in the path of said strings and being adapted to yield upon engagement with the same. 90

2. In a device of the class described, the combination with two relatively movable members, one of said members having a series of strings mounted thereon, the other member having a flat side, of a flat strip of elastic material secured at its ends to the flat side of the last mentioned member, and having an opening in its intermediate portion, and a plectrum extending through said opening and having a rounded head disposed between the flat side of said last mentioned member and the inner side of said strip, said plectrum being disposed in the path of said strings and being adapted to yield upon engagement with the same, the rounded head of said plectrum having a rolling motion with respect to the flat side of said last mentioned member when such yielding takes place. 105

In testimony whereof I have hereunto set 110 my hand in the presence of two subscribing witnesses.

GRANVILLE A. HEIMER.
